Primary Examiner — Janice Hallmark*Assistant Examiner* — Adedoyin Taiwo Odeyale(74) *Attorney, Agent, or Firm* — Toohey Law Group, LLC; Kevin D. Mandro(57) **CLAIM**

The ornamental design for a fluid administration apparatus assembly, as shown and described.

DESCRIPTION

FIG. 1 is a front, bottom, left side perspective view of the fluid administration apparatus assembly showing the new design;

FIG. 2 is a front, top, right side perspective view thereof;

FIG. 3 is a front elevational view thereof;

FIG. 4 is a rear elevational view thereof;

FIG. 5 is a left side elevational view thereof;

FIG. 6 is a right elevational view thereof;

FIG. 7 is a top plan view thereof; and,

FIG. 8 is a bottom plan view thereof.

Broken lines illustrate portions of the fluid administration assembly that form no part of the claimed design.
